UNITED STATES PATENT OFFICE.

JOHN H. THOMPSON, OF GREENVILLE, OHIO.

BRUSH-HOLDING DEVICE.

1,153,730.

Specification of Letters Patent. Patented Sept. 14, 1915.

Application filed August 26, 1914. Serial No. 858,694.

To all whom it may concern:

Be it known that I, JOHN H. THOMPSON, a citizen of the United States, residing at Greenville, in the county of Darke and State 5 of Ohio, have invented certain new and useful Improvements in Brush-Holding Devices; and I do hereby declare the following to be a full, clear, and exact description of the invention, such as will enable others 10 skilled in the art to which it appertains to make and use the same, reference being had to the accompanying drawings, and to the letters and figures of reference marked thereon, which form a part of this specification.

15 This invention relates to new and useful improvements in devices for holding brushes of various kinds, affording means whereby the bristles may be protected and consists of means whereby distortion and discoloration 20 of the bristles may be prevented by keeping them out of contact with the sides or bottom of the receptacle containing water or other liquids and in which they are placed for protection when not in use.

25 My invention is illustrated in the accompanying drawings, in which:

Figure 1 is a perspective view of the device in a closed relation. Fig. 2 is a view in perspective showing the sections open. 30 Fig. 3 is a longitudinal sectional view showing the brush adjusted in place, and Fig. 4 is a cross sectional view.

Reference now being had to the details of the drawings by letter, A and B designate 35 the two parts of the brush holder, made of any suitable material, the two sections each having flanges C, and D respectively, the flanges being pivoted together as shown. The section B is slightly narrower than the 40 section A in order to allow the same to fold

in the manner shown in Fig. 1 of the drawings. The upper portions of the flanges of each section are corrugated as at E and are adapted to interlock with one another when the sections are closed or in the position shown 45 in Fig. 1. The two sections converge toward their lower ends and are adapted to frictionally hold a brush H intermediate the end walls with the ends of the bristles a slight distance above the open bottom of 50 the device.

It will be noted that by the provision of a device embodying the features of my invention, a simple and efficient means is afforded whereby a brush of any kind may be securely held so that the bristles will be protected, the latter being held from contact 55 with the bottom or sides of a receptacle in which the brush may be contained with liquid for protection, thereby keeping the 60 bristles from discoloration.

What I claim to be new is:—

A brush holding device comprising two sections having flanges upon the opposite sides only, the upper free end of each flange 65 being provided with corrugations, pivotal pins passing through the flanges a slight distance above corresponding ends, the flanges of one section adapted to swing inside the flanges of the other, the said corrugations 70 being adapted to frictionally engage one another to hold the sections together to form a brush holding receptacle.

In testimony whereof I hereunto affix my signature in presence of two witnesses.

JOHN H. THOMPSON.
